UNITED STATES PATENT OFFICE.

JAMES G. DELANEY, OF NEW YORK, N. Y.

HOISTING AND CONVEYING DEVICE.

SPECIFICATION forming part of Letters Patent No. 752,442, dated February 16, 1904.

Application filed December 28, 1901. Serial No. 87,564. (No model.)

To all whom it may concern:

Be it known that I, JAMES G. DELANEY, a citizen of the United States, and a resident of New York city, borough of Manhattan, in the county of New York and State of New York, have invented a new and Improved Hoisting and Conveying Device, of which the following is a full, clear, and exact description.

My invention relates to improvements in hoisting and conveying devices, and is herein illustrated as applied to a cableway, although it is evident that it may be employed as well in connection with any other form of tramway.

My invention comprises the novel features hereinafter described and particularly pointed out in the claims.

Reference is to be had to the accompanying drawings, forming a part of this specification, in which similar characters of reference indicate corresponding parts in all the figures.

Figure 1 is a side view of a cableway constructed in accordance with my invention. Fig. 2 is a side elevation of engine-drums such as are required for operating such a cableway. Fig. 3 is a sectional side elevation of the carriage, taken between the side plates or frames thereof, dotted lines H being added to indicate the position of the hoist-actuating rope. Figs. 4 and 5 are end and side elevations of a modified form of carriage. Fig. 6 is a top plan view of the block carrying the carriage-operating ropes at the tail end of the cableway.

A carriage C is provided with wheels 1 2, adapted to run upon any suitable form of trackway, said trackway, as shown, consisting of the supporting-cable A. A traction-rope B of the usual endless type is provided, by means of which the carriage may be caused to travel along the trackway as desired. At the head-support or tower the runs of this rope pass, respectively, over the pulleys 3 and 4 and then about a drum E of the engine, which is loosely mounted upon its shaft and is driven by a friction device F and is supplied with a friction-brake G, by which it may be held against turning. At the tail-support or tower the traction-rope passes about one of the sheaves 5, contained in the block 6.

The carriage-frame is herein for simplicity shown as consisting of two plates. Between these plates are journaled the wheels 1 and 2, which run upon the trackway and support the carriage, and the chain or hoisting pulley, 55 sheave, or drum 8, which should preferably be a pocket or a sprocket wheel, which is adapted to engage the hoisting-chain I. When the hoisting member 8 is of the pocket or sprocket form shown it constitutes a clutching hoist member, which progressively clutches and releases the load-suspender I within each cycle of movement, and therefore enables the point of suspension of the fall to be maintained in a laterally constant position with respect to the 60 vertical plane through the supporting-cable A. Journaled upon the carriage is a wheel 7, which is adapted to receive a sufficient number of wraps of a hoist-operating rope H so that power may be conveyed by the frictional grip 70 of the ropes thereon to raise the load. This rope is an endless one, passing about the pulley 5 at the tail-support, one run passing over each of the pulleys 9 and 10 at the head-support and then passing about the drum D at the engine. 75 This drum is shown as keyed to the shaft, although it may be provided with a friction-drive and a brake, if desired. It will be observed that in operation the run of the hoist-operating rope H between the sheave 7 and one end of 80 the trackway will perform the function of a hoisting-rope, while the run of the rope H between the sheave 7 and the other end of the trackway will perform the function of a slack-pulling rope to prevent the sagging of the 85 hoisting-run of the rope H during the lowering of the fall. Thus in Fig. 3 the run of rope H shown in dotted lines at the left of the sheave 7 constitutes the hoisting-rope, in fact, while the run of the rope H shown in dotted 90 lines at the right of the sheave 7 constitutes, in fact, a slack-pulling rope, because in lowering the fall it, in fact, outhauls the hoisting-rope, and thus supports it from sagging.

Power is communicated by any suitable 95 mechanism from the sheave 7 to the chain-wheel 8. The means herein shown consist of the pinion 11 and gear 12, secured to the respective shafts or so as to turn, respectively, with sheave 7 and chain-wheel 8. A chain 100

storage-drum 14 is provided, which is geared to turn with the chain hoist-wheel 8 and takes in and pays out the chain approximately as the chain-wheel 8. With the two geared together by the gears 12 and 16, as shown, the rate of actuating the chain will vary; but the variation in rate will be accounted for in the loop which hangs between. Small guide-pulleys 13, placed one on each side of the chain 10 close to the wheel 8, take any side pull and prevent the chain from being pulled off of the chain-wheel. A clevis 15 may also be secured to the frame and one end of the chain attached thereto and a fall-block be suspended in the 15 loop formed between said clevis and the chain-wheel. This will increase the hoisting power of the device over the direct attachment of the load to the end of the chain.

In Figs. 4 and 5 a modified form is shown, 20 in which two chain hoist and chain storage wheels are employed, one pair on each side of the carriage, and the rope or driving wheel 7 is placed between the carriage-frames. In this construction there are two hoisting-chains 25 I I', respectively pendent from the two parts 8 8 of the hoist on the load-carriage and connected together at the bottom by a yoke 20, which is provided at the middle with a load-supporting hook 21. This construction has 30 the advantage of maintaining the load attachment 21 substantially in the vertical plane of the wheels 1 2 even though the winding of the suspenders I I' upon the hoist parts 8 8 should vary the distance between them. Where the 35 fall consists of only a single suspender I, there is no means of compensating for any sidewise variation from the vertical plane of the wheels; but where the fall consists of the two suspenders II', yoked together, as in Fig. 4, it enables 40 the two parts 8 8 of the hoist to be so constructed that any sidewise movement of one suspender in the course of winding or unwinding can be compensated for by an inverse sidewise movement of the other suspender, so that 45 the resultant may maintain the load-support 21 constantly in the same vertical plane.

In connection with the engine in Fig. 1 I have shown a means for taking up slack or applying tension to the operating - ropes. 50 This consists in a wheel 16', which receives one of the wraps of the rope passing about the engine-drum, said wheel being adjustable in any convenient way toward and from the engine-drum. The means shown, although 55 not the only means which may be used, consists in journaling the wheel in a frame 17, which is mounted to slide on guides and is controlled in position by the threaded rod 18. At the tail end of the cableway another means 60 for adjusting tension on the ropes is shown. This consists in journaling the sheaves 5, about which these ropes pass, in a block 6, which is clamped upon the main cable A. This block has ears for the attachment of ropes or chains

by which it may be pulled back until the ropes 65 are sufficiently tightened.

It will be noted that by the use of a chain hoist-wheel and a chain storage-wheel the pull of the load is always upon the same point and does not shift laterally of the direction of the 70 cableway. In cableway-carriages containing a drum which is both a hoisting and a storing drum the position of the hoist-rope varies laterally with respect to the plane which includes the supporting-cable and is perpendicular to the hoisting-drum axis. As the hoisting-rope varies from this plane it throws a side strain upon the drum, which as the carriage is suspended tends to cause the hoisting-rope to run off the end of its drum. This 75 tendency is sufficient to prevent the practical operation of devices of this character. The side strain has in such cases been sufficient to make a cable climb over flanges of considerable depth.

By my invention the draft of the hoisting-chain is kept at all times in a direct line beneath the supporting or trackway rope and there is no side strain tending to pull the chain off of its wheel. The avoidance of side draft 90 might be secured by having the chain coil upon itself; but this would greatly vary the power of the hoist, which result would ordinarily be very objectionable. By my construction the draft is always central and the 95 power is constant. By using a chain of sufficient length it is possible to bring in loads from a great distance in either side of the line of the cableway, thus increasing its efficiency. To take the side strain necessary to swing the 100 carriage into line with the strain in such cases, the guide-rollers 13 are provided on each side of the chain. These are not needed after the chain becomes strained, as then the carriage swings so that the draft is central.

While I have herein shown the storage-wheel as geared to the hoist-wheel, it is evident that it may be turned by a frictional connection therewith, in which case its speed may be varied by permitting slip, or it may 110 be connected directly with the wheel 7, over which the hoist-operating rope passes.

I have only shown and described the use of a chain for hoisting purposes, not that a rope may not be used, but because a chain lends 115 itself to use with a simple hoist mechanism of the character desired better than a rope does. A grip-wheel or double hoist-drums might, however, be used with a rope instead of the pocket-wheel and chain.

Since various features of my invention may be employed, omitting others, and the parts or elements may be varied to a great extent, I do not wish to be understood as limiting myself to exclude such omissions or variations.

Having thus fully described my invention, I claim as new and desire to secure by Letters Patent—

1. A hoisting device comprising a chain hoist-wheel, a chain storage-wheel driven in unison therewith, and driving means for said chain-wheels adapted to be operated by a passing rope. 5
2. A cableway-carriage having thereon supporting or trackway-engaging wheels, a chain hoist-wheel and a chain storage-wheel adapted to be turned in unison, all of said wheels being located in a common plane. 10
3. A cableway-carriage having thereon supporting or trackway-engaging wheels, a chain hoist-wheel and a chain storage-wheel adapted to be turned in unison, all of said wheels being located in a common plane, and means for operating said chain-wheels by a rope from a distance. 15
4. A cableway-carriage having a load-suspender, supporting and hoisting means adapted to preserve the point of suspension of the load in a substantially constant position relative to the vertical plane through the trackway, a distinct suspender storage means carried by the carriage and means for actuating the hoisting and storing mechanism from a distance. 20
5. In a cableway-carriage in combination, a chain hoist-wheel, a chain storage-wheel, and a driving-wheel adapted to receive wraps of an endless rope and turned thereby, and means for connecting the other wheels to be driven from the said driving-wheel. 30
6. In a cableway in combination a carriage, a traction-rope therefor, a hoist-chain, separate chain hoisting and storing wheels, a driving-pulley having driving connection with the chain-wheels, a hoist-operating rope having wraps passing about said driving-pulley, and means for operating the hoist-operating and traction ropes separately. 35
7. In a conveying apparatus, in combination, a trackway, a rope-actuating engine, a load-carriage, a hoist on said carriage, a combined hoisting and slack-pulling endless rope connecting said hoist with the engine and a tension-sheave in a loop of said endless rope. 40
8. In a conveying apparatus, in combination, a single trackway, a load-carriage, a two-part hoist, mounted on said carriage, a fall consisting of two suspenders each pendent from one of said hoist parts and a hoisting-rope whereby said hoist is operated. 55
9. In a conveying apparatus, in combination, a single trackway, a load-carriage, a two-part hoist mounted on said carriage, a fall consisting of two suspenders each pendent from one of said hoist parts, a hoisting-rope whereby said hoist is operated and a slack-pulling rope whereby sag of said hoisting-rope is prevented. 60
10. In a conveying apparatus, in combination, a single trackway, a load-carriage, a wheel by which said carriage is supported on said trackway, a two-part hoist the parts of which are mounted on said carriage on opposite sides of the normally central vertical plane thereof, a fall consisting of two suspenders each pendent from one of said hoist parts and a hoist-operating rope. 65
11. In a conveying apparatus, in combination, a single trackway, a load-carriage, a two-part hoist mounted thereon, a sheave connected with the two parts of said hoist between the same, a hoisting-rope and a slack-pulling rope engaging said sheave and a two-part fall pendent from said two-part hoist. 70
12. In a hoisting and conveying apparatus, in combination, a trackway, a load-carriage traveling thereon, a motor, outward and inward runs of rope actuated by said motor, a load-suspender, a clutching hoist member mounted on said carriage and progressively clutching and releasing said load-suspender within each cycle of movement. 75
13. In a hoisting and conveying apparatus, in combination, a trackway, a load-carriage traveling thereon, a motor, outward and inward rope runs actuated by said motor, a load-suspender, a clutching hoist member mounted on said carriage and progressively clutching and releasing said load-suspender within each cycle of movement and power-multiplying mechanism mounted on said carriage and interposed between said runs of rope and said clutching hoist member. 80
- In testimony whereof I have signed my name in the presence of two subscribing witnesses. 85
